PENCIL POINTING DEVICE

William K. Crownfield, Franklin Township,
Somerset County, N. J.

Application June 16, 1944, Serial No. 540,637

6 Claims. (Cl. 120—89)

This invention relates to a pencil pointing device and more particularly to a small device of this character that can readily and quickly be used any number of times without material inconvenience to the user.

Many types of work require that the worker have a sharply pointed pencil at all times. For example, draftsmen and accountants require sharply pointed pencils at all times. The usual pencil sharpener not only points the lead, but also removes a great deal of the lead as well as the surrounding wood and is not only usually inconveniently placed but very wasteful both of the pencil, and of the user's time. The usual files and abrasive pads now commonly used to re-point the leads of pencils are unsatisfactory in many respects. They usually provide no receptacle for the refuse or grindings, and provide no guiding medium or provision for facilitating forming of a proper point upon the lead.

It is the purpose of this invention to provide an improved pencil pointer particularly adapted to re-pointing the lead of a pencil, and free from the disadvantages of devices of this character as heretofore known. The advantages of a pencil pointer embodying the principles of this invention will be more apparent from the following description given in connection with the drawing in which:

Fig. I is a perspective view of a pencil pointer constructed in accordance with this invention.

Fig. II is a section taken on line A—A of Fig. I; and

Fig. III is a view similar to Fig. II of a modified form of this invention.

As can be seen from Fig. I, the pencil pointer of this invention comprises essentially a file member 1, preferably for most purposes a flat file, mounted in a relatively long narrow tray 2. The ends of the tray are raised and grooved vertically as at 3 to receive the end portions of the file 1 and support and retain the latter horizontally with the filing surfaces disposed vertically. The file may be retained in the slots by any suitable adhesive or by frictional fit.

The tray 2 may be made of wood, metal, plastic or any other suitable material and is preferably about three inches long and of such proportions relatively to the file that the latter projects about one-eighth or three-sixteenths of an inch above the top edges 4 of the side walls of the tray. The end walls of the tray are raised as previously stated to the level of the top edge of the file as shown in Fig. I to provide greater support and also protection. Preferably there is a slight

clearance between the bottom edge of the file and the bottom of the tray to facilitate cleaning of the tray.

In Fig. III, there is shown a slightly modified form of this invention in which a tray 5 is fitted with triangular file 6 instead of a flat file. In this form, the file is set with an apex down, that is, with a horizontal top surface and two inwardly inclined side surfaces. This form has some advantages when the usual wood or mechanical pencils are being pointed and provides more protection for the dirty surfaces of the file. The form disclosed in Figs. I and II is adaptable to all types of pencils and to draftsman's instruments as well and is, therefore, more universal in its application.

In use, the lead of the pencil is brought into contact with the file surface at a sharp angle; by resting the pencil upon the upper edge 4 of 20 one side wall 2, as shown in Figs. I and III (and upon upper edge 7 in Fig. III), using the latter as a guide or rest; and stroked across the length of the file once or twice. By rotating and stroking at the same time, a needle-like point is obtainable, whereas by stroking without rotating the pencil about its own axis, a knife-like or chisel-point edge is formed. The lead particles fall into the bottom of the tray and are there confined until the tray is emptied.

30 From the foregoing, it will be apparent that there is provided an efficient, conveniently usable and simply constructed portable pencil pointer, using a minimum number of parts that can be manufactured and assembled very cheaply, and 35 one in which the proportions are such that the soiled surfaces of the file are, for the most part, not readily accessible so as to be likely to be touched by the user. Other advantages will be apparent to those skilled in the art, to whom it 40 will also be apparent that minor changes can be made in the details of construction without departing from the spirit and scope of this invention as defined in the appended claims.

Having described my invention, I claim:

- 45 1. A portable pencil pointing device comprising a relatively long narrow tray, having side and end walls said end wall having means for supporting a file within said tray, and a flat file supported at its ends by said supporting means 50 in said tray lengthwise thereof and with its file surfaces between and parallel to the side walls of said tray, the top edges of said side walls serving as a rest for the pencil as it is being pointed.
2. A portable pencil pointing device comprising 55 a relatively long narrow tray, having side and

end walls, the end walls being provided with vertical grooves, and a flat file within said tray and having its ends engaged in said grooves for supporting the file with its filing faces between and parallel to the side walls of the tray and with the top of the file slightly above the side walls of the tray, the top edges of said side walls serving as a rest for the pencil as it is being pointed.

3. A portable pencil pointing device comprising a relatively long narrow tray having side and end walls, the end walls extending above the side walls and being provided with means for supporting a file within said tray, and a flat file within said tray and having its ends engaged by said supporting means for supporting the file with its filing faces between and parallel to the side walls of the tray and with the top of the file slightly above the side walls of the tray, the top edges of said side walls serving as a rest for the pencil as it is being pointed.

4. A portable pencil pointing device comprising a relatively long narrow tray having side and end walls, the end walls extending above the side walls and being provided with vertical grooves, and a flat file within said tray and having its ends engaged in said grooves for supporting the

file with its filing faces between and parallel to the side walls of the tray and with the top of the file slightly above the side walls of the tray and with the lowermost edge of the file free from the bottom of the tray, the top edges of said side walls serving as a rest for the pencil as it is being pointed.

5. A portable pencil pointing device comprising a relatively long narrow tray having side walls, and a file supported in said tray lengthwise thereof and parallel to the side walls of the tray, said file having inclined side file surfaces arranged at an angle to said side walls, the top edges of the latter serving as a rest for the pencil as it is pointed.

10 6. A portable pencil pointing device comprising a relatively long narrow tray having side walls, and a file supported in said tray lengthwise thereof and parallel to the side walls of the tray, said file having inclined side file surfaces being arranged with said surfaces inclined inwardly and downwardly with respect to the bottom of said tray, the top edges of said side walls serving as a rest for the pencil as it is being pointed.

15 20 25 WILLIAM K. CROWNFIELD.
